UNITED STATES PATENT OFFICE.

PAUL N. BOSSART, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed June 30, 1926. Serial No. 119,617.

My invention relates to railway traffic controlling apparatus, and particularly to apparatus of the type comprising train carried governing means controlled by train controlling current flowing in the trackway.

One object of my present invention is the provision of apparatus of the type described which is immune to the effects of stray currents flowing in the trackway or in adjacent conductors such as transmission lines etc.

I will describe one form of railway traffic controlling apparatus embodying my invention, and will then point out the novel features thereof in claims.

15 The accompanying drawing is a diagrammatic view, illustrating one form of railway traffic controlling apparatus embodying my invention.

Referring to the drawing, the reference 20 characters 1 and 1^a designate the track rails of a stretch of railway track. These rails are at times supplied with alternating train controlling current from a suitable source such as an alternator G which is connected 25 across the rails through a circuit controller 21. In actual practice the circuit controller 21 will usually be controlled by traffic conditions. When this circuit controller is closed alternating train controlling current 30 is supplied to the track rails, and when the circuit controller is open this supply is interrupted.

Carried on the train are two magnetizable cores 2 and 2^a located in inductive relation 35 with the two track rails 1 and 1^a, respectively. Core 2 is provided with a winding 3, and core 2^a is provided with a similar winding 3^a, these two windings being connected in series in such manner that the voltages induced therein by train controlling 40 currents flowing in the two track rails 1 and 1^a at an instant are additive. The windings 3 and 3^a control an amplifier A. In the form here shown this amplifier is of the microphone type and comprises a permanent magnet 7 and a vibrating armature 8. The armature 8 carries a winding 6 which is connected with windings 3 and 3^a through a condenser 4 and a resistance 5. The circuit including the windings 3 and 3^a, the condenser 45 4, the resistance 5, and the operating winding 6 of the amplifier A is designated in general by the reference character D, and I shall refer to this circuit hereinafter as the

“pick-up” circuit. The armature 8 of the 55 amplifier A controls a microphone unit B comprising a fixed tube 27 of insulating material containing a conducting plug 9. A mass 10 of carbon granules or grains is interposed between this plug 9 and a movable 60 plunger 11 of conducting material which is operatively connected with armature 8. It will therefore be plain that vibration of the armature 8 will cause a movement of the plunger 11 which will in turn vary the pressure 65 on the carbon granules 10 and will therefore vary the resistance of the microphone unit. The primary 12 of a transformer T is connected in series with a source of direct current, such as a battery 13, and the microphone unit B, so that operation of the amplifier A causes pulsations in the current supplied to the primary of the transformer.

The secondary 14 of transformer T supplies 70 energy to a filter circuit designated in general by the reference character J and comprising an auto-transformer M and a condenser 16. A direct current relay K is connected with windings 18 and 19 of transformer M through rectifiers 20 and 21 so that alternating current flowing in the transformer M due to pulsations in the current in winding 12 of transformer T energizes 75 relay K.

The parts are so arranged that the reactive 80 impedance of winding 17 of transformer M is very high compared with the reactive impedance of windings 18 and 19, and the circuit is tuned by means of condenser 16 so that the circuit J comprises a band pass filter 85 of the simple resonant circuit type. The parts are further proportioned so that the decrement of the filter circuit is low in order to obtain sharp filtering.

Relay K controls governing means of any 90 suitable form, here shown as two lamps 24 and 25. When relay K is energized, current flows from a suitable source of energy, such as a battery 22, through front contact 23-23^a of relay K and lamp 24. When relay K is de-energized back contact 23-23^b is closed and current flows from battery 22 through lamp 25.

When train controlling current is flowing 100 through the track rails the voltages induced in windings 3 and 3^a cause a current in the pick-up circuit D which operates the amplifier A. The resulting pulsations in the pri-

mary 12 of transformer T cause an alternating current in the filter circuit J which energizes relay K and causes lamp 24 to become lighted. When the supply of train controlling current to the trackway becomes interrupted the operation of the amplifier A is discontinued and relay K becomes de-energized, thereby lighting lamp 25.

Under some conditions of operation it may happen that currents are created in the pick-up circuit D when no train controlling current is being supplied to the track rails. This may result from stray alternating currents in the track rails, or it may occur from heavy pulsations of direct or alternating currents either in the track rails or in conductors adjacent the trackway. In the absence of any preventative means these currents cause improper operation of the train carried lamps. I therefore proportion the various parts of the train carried apparatus in such manner that the effect of these stray currents is successively diminished as the currents pass through the apparatus so that their effect upon relay K is negligible. By means of the condenser 4 the pick-up circuit D is tuned to resonance at a frequency slightly below the frequency of the train controlling current. By means of the resistance 5 this pick-up circuit is adjusted to have a high decrement so that the alternating current created in the pick-up circuit by pulse excitation from surges of stray currents will die down rapidly. I also construct the amplifier A so that it is mechanically untuned. The purpose of this construction is to prevent mechanical shocks due to heavy pulses of current in the pick-up circuit from setting up in the amplifier vibrations of the frequency of the train controlling current. It follows that the effect of stray currents induced at train control frequency in the pick-up circuit by heavy surges of current in the vicinity of the pick-up circuit is greatly reduced, both as to amount and as to the length of time the excitation from any one pulse will be of sufficiently high value to actuate the microphone through its normal amplitude.

It is well known that at a given frequency, the output of a microphone amplifier has a definite saturation point and that increasing the input to winding 6 above this definite saturation point will cause substantially no increase in the output of the amplifier. On the other hand, an increase in the input to the amplifier above this saturation point will react to detune the pick-up circuit, because of the variation in the permeability of the magnetizable cores 2, 2^a, and the magnet 7 and armature 8 in response to variations in the magnetizing force. The effect of this detuning is to lower the resonant frequency of the circuit and it follows that the effect of surges on the amplifier is to increase the

difference between the resonant frequency of the circuit D and the frequency of the train controlling current.

The parts are so proportioned that for normal values of train controlling current the amplifier A operates just below the saturation point. It follows that increased currents in the pick-up circuit due to stray currents in this circuit simultaneous with the currents induced in this circuit by train controlling current will not cause a substantial increase in the output of the amplifier but may even cause a slight decrease in the output.

Due to the sharp tuning and low decrement of the filter circuit J, should any surge pass the amplifier A, a considerable time, that is, a considerable number of cycles, is required before the resulting current will build up in circuit J to the value required to operate relay K.

Furthermore the circuit J is tuned to resonance at a frequency slightly greater than the frequency of the train controlling current so that the difference between the resonant frequencies of circuits D and J is considerable, though neither is sufficiently mistuned to the train controlling current to substantially affect the resonant response to current of train control frequency.

Considering the operation of the apparatus as a whole, it will be seen that stray currents caused by shock excitation of circuit D will be of the frequency to which this circuit is tuned, and therefore slightly below the frequency of the train controlling current. Due to the high decrement of circuit D this current will die out very rapidly. During the first few cycles of this stray current amplifier A may be operated, but the amplifier will be saturated and will not increase its output. The reaction of the pick-up circuit to large currents flowing in itself will further mistune the pick-up circuit. The only effect of the free oscillations in circuit D, therefore, is to create stray current of a similar frequency in the transformer T and hence in the filter circuit J. But the stray current will be of considerably lower frequency than the frequency to which the filter circuit is tuned and the filter will therefore substantially block the stray current. Furthermore, due to the sharp tuning and low decrement of circuit J, the stray current in circuit D will have died out before the resulting current in relay K has grown to an amount sufficient to energize the relay. The effect of stray currents upon relay K is therefore negligible.

It will be plain from the foregoing that if no train controlling current is being supplied to the track rails, stray transient currents induced in the pick-up circuit D will not operate relay K to give a false indication by lighting lamp 24. Similarly, a con-

tinuous altering current induced in the pick-up circuit D even if sufficient in magnitude to operate amplifier A through its normal or even greater amplitude, can create 5 only a predetermined value of pulsating current in primary 12. But the resulting current in secondary 14, unless very close to the frequency band passed by the filter circuit J, will be so attenuated that it will 10 be insufficient to operate relay K.

Although I have herein shown and described only one form of railway traffic controlling apparatus embodying my invention, it is understood that various changes and 15 modifications may be made therein within the scope of the appended claims without departing from the spirit and scope of my invention.

Having thus described my invention, what 20 I claim is:

1. Railway traffic controlling apparatus comprising a transformer, means on the train controlled from the trackway for supplying energy to the primary of said transformer, a reactance and a condenser connected in series with the secondary of the 25 transformer, and governing means controlled by the voltage across a portion of said reactance.

2. Railway traffic controlling apparatus comprising a transformer, means on the train controlled from the trackway for supplying energy to the primary of said transformer, a tuned filter circuit for the secondary of said transformer including a condenser and an auto-transformer, and governing means controlled by said auto-transformer.

3. Railway traffic controlling apparatus comprising a tuned pick-up circuit on the train receiving energy from the rails, governing means on the train, a tuned filter circuit for controlling such governing means, and a mechanically untuned microphone 40 amplifier for transferring energy from said pick-up circuit to said filter circuit.

4. In combination, a stretch of railway track supplied with alternating train controlling current, a tuned pick-up circuit on 50 a train receiving energy from the trackway, an amplifier controlled by said pick-up circuit and substantially saturated by normal values of said train controlling current, governing means on the train controlled by said amplifier, and a band pass filter interposed between said amplifier and said governing means, said pick-up circuit being tuned to resonance at a frequency slightly different from the output frequency of said filter.

5. In combination with a stretch of track supplied with alternating train controlling current, a train carried pick-up circuit inductively related to the trackway, and tuned 60 to resonance at a frequency slightly below the frequency of said train controlling cur-

rent, a filter circuit tuned to resonance at a frequency slightly above the frequency of said train controlling current, an amplifier for transferring energy from said pick-up circuit to said filter circuit and governing 70 means controlled by said filter circuit.

6. In combination with a stretch of track supplied with alternating train controlling current, a train carried pick-up circuit inductively related to the trackway and tuned 75 to resonance at a frequency slightly below the frequency of said train controlling current, a filter circuit tuned to resonance at a frequency slightly above the frequency of said train controlling current, a mechanically untuned microphone amplifier for transferring energy from said pick-up circuit to said filter circuit, and governing 80 means controlled by said filter circuit.

7. In combination with a stretch of track supplied with alternating train controlling current, a train carried pick-up circuit inductively related to the trackway, and tuned to resonance at a frequency slightly below the frequency of said train controlling current, a mechanically untuned microphone amplifier controlled by said pick-up circuit and substantially saturated at normal values 90 of the train controlling current, a train carried relay, a band pass filter interposed between said amplifier and said relay, and governing means controlled by said relay.

8. In combination with a stretch of railway track supplied with alternating current, a tuned pick-up circuit receiving energy from the trackway, an untuned amplifier controlled by said pick-up circuit, a tuned filter circuit receiving energy from said amplifier, and a relay controlled by 100 said filter circuit, said pick-up circuit having a high decrement and said filter circuit having a low decrement so that the currents caused in the pick-up circuit by a surge of energy in the trackway will die out before the resulting currents in the filter circuit 105 grow to a magnitude sufficient to energize said relay.

9. In combination with a stretch of railway track supplied with alternating current, a magnetizable core located in inductive relation with the track rails, a winding on said core, a pick-up circuit including said winding and normally mistuned slightly to the frequency of such current so that the variation in the permeability of said core 110 due to a surge of energy in the trackway will further mistune said pick-up circuit, an amplifier controlled by the pick-up circuit, a relay, and a band pass filter interposed between said relay and said amplifier.

10. In combination with a stretch of railway track supplied with alternating current, a tuned pick-up circuit receiving energy from the trackway, an untuned amplifier controlled by said pick-up circuit and sub- 115 120 125 130

stantially saturated at the normal values of the alternating current in the railway track, a tuned filter circuit receiving energy from said amplifier, and a relay controlled by said filter circuit, said pick-up circuit having a high decrement and said filter circuit having a low decrement so that the cur-

rents caused in the pick-up circuit by a surge of energy in the trackway will die out before the resulting currents in the filter circuit 10 grow to a magnitude sufficient to energize said relay.

In testimony whereof I affix my signature.
PAUL N. BOSSART.
